EVAPORATOR HEADER CONSTRUCTION

Bernard C. Johnson, Libertyville, Ill., assignor to
Houdaille-Hershey Corporation, Detroit, Mich.,
a corporation of Michigan

Application April 4, 1941, Serial No. 386,855

10 Claims. (Cl. 62—126)

This invention relates to evaporators or heat exchangers having divided header chambers.

More specifically the invention relates to sheet metal evaporator units having chambers with baffles or dividing walls therein for separating the chambers into a plurality of compartments.

In mechanical refrigerator systems it is highly desirable to utilize as much of the heat absorbing capacity of the refrigerant as possible directly in the evaporator unit so that the spent refrigerant which is passed back to the compressor will not cause a frosting of the return tubes. In systems where liquid refrigerant is allowed to boil off or gasify in the evaporator unit there is a tendency for unspent refrigerant to be entrained with the spent refrigerant gases or vapor as the same pass through the return tube to the compressor thereby cooling this tube and causing frost to form on the exterior of the tube.

In accordance with the present invention the entrainment of unspent refrigerant with the gases or vapor in the return tube is completely eliminated or minimized by dividing the header chambers of the evaporator unit into a plurality of compartments which successively receive the refrigerant so that, by the time the refrigerant reaches the return tube, it is completely spent.

A feature of the invention resides in the provision of a vertical baffle plate in the header chamber of an evaporator unit to divide the chamber into two compartments one of which receives refrigerant from the distributing ducts of the evaporator and the other of which communicates with the return or exhaust tube leading to the compressor. The upper portions of the two compartments are joined by a small opening provided in the baffle.

It is, then, an object of this invention to prevent or minimize frost back in mechanical refrigerator systems by dividing the header chambers of evaporator units in said systems into compartments successively receiving the refrigerant.

A further object of this invention is to provide an evaporator unit having a multi-compartment header chamber.

Another object of the invention is to provide a header construction for evaporator units with a dividing wall or baffle separating each header chamber into a plurality of compartments.

A specific object of the invention is to provide sheet metal evaporator units having embossed portions defining a header chamber with a sheet metal dividing wall between the embossed portions for forming therewith a multi-compartment chamber.

Another object of the invention is to sandwich a sheet of metal between the walls of a sheet metal evaporator unit for extending across embossed portions of the unit to divide the chamber provided by said embossed portions into a plurality of compartments.

Another object of the invention is to divide a single header chamber in an evaporator unit into a liquid-receiving compartment and a gas-receiving compartment for preventing discharge of unspent refrigerant from the unit.

Other and further objects of the invention will become apparent to those skilled in the art from the following detailed description of the annexed sheets of drawings which, by way of example, illustrate a preferred form of the invention. It will be understood that the invention is not limited to the illustrated preferred form since the construction can be varied greatly without departing from the scope of the invention.

On the drawings:

Figure 1 is a rear end elevational view of a sheet metal evaporator unit having a header construction according to this invention.

Figure 2 is a side elevational view of the evaporator unit shown in Figure 1.

Figure 3 is a fragmentary enlarged side elevational view of the evaporator unit shown in Figures 1 and 2 and better illustrating the header construction of the unit.

Figure 4 is a horizontal cross-sectional view taken along the line IV—IV of Figure 3.

Figure 5 is a vertical cross-sectional view taken along the line V—V of Figure 3.

Figure 6 is a broken side elevational view of the baffle or dividing wall mounted in the header construction of this invention.

As shown on the drawings:

In Figures 1 and 2, the reference numeral 10 designates generally an evaporator unit composed of an inner metal sheet 11 and an outer metal sheet 12. The sheets 11 and 12 are secured together by brazing, spot-welding, stitch-welding or the like. The evaporator unit 10 is U-shaped as best shown in Figure 1 to define the side walls and bottom of a sharp freezing chamber 13. A shelf 14 composed of sheet metal is mounted in the sharp freezing chamber and bridges the space between the side walls. It can be provided with downturned flanges 14a at the side edges thereof receiving rivets 15 therethrough which also extend through the side walls of the unit to fixedly unite the shelf to the unit.

The top ends of the side walls can be bent horizontally inward to provide horizontal flanges 16

for receiving suspension means to hang the unit from the top wall of a refrigerator cabinet.

As shown in Figures 1 to 5, the outer sheet 12 has substantially rectangular shallow embossments 17 formed thereon near the top of each side wall of the unit and extending from closely spaced relation to the front end of the unit into greater spaced relation from the rear end of the unit as best shown in Figure 2. Each embossment 17 has semi-cylindrical additional embossments 18 within the confines thereof and extending outwardly from the embossments 17 as best known in Figures 1, 4 and 5.

The inner sheet 11 has complementary rectangular embossments 19 and semi-cylindrical embossments 20 registering with the embossments 17 and 18 respectively.

In accordance with this invention and as best shown in Figures 4 to 6, a substantially rectangular metal plate 21 is sandwiched between the sheets 11 and 12 and fitted into rectangular embossments 17 and 19 of these sheets. The plate extends vertically through the chamber provided by the embossments 18 and 20 as best shown in Figure 5 to divide this chamber into compartments 22 and 23.

The plate 21 has an aperture 21a therethrough near the top thereof at the end of the plate which is positioned adjacent to the front end of the evaporator 10 as best shown in Figures 3 and 4.

It will, of course, be understood that a similar plate 21 is provided in the other walls of the evaporator unit to divide the other chamber into a pair of compartments 22 and 23.

The outer sheet of the unit 10 has a plurality of spaced flutes 24 embossed therein providing refrigerant circulating ducts or passageways communicating at their upper ends with the bottom of the compartment 22 of each header chamber.

A flute 25 is embossed in the bottom wall portion of the outer sheet 12 to provide an inlet manifold to the ducts defined by the flutes 24. Liquid refrigerant is supplied to this inlet manifold through a tube 26 entering the rear end of the flute 25 as best shown in Figures 1 and 2. Refrigerant thus circulates from the inlet tube through the ducts provided by the flutes 24 and 25 along the bottom and side walls of the unit to the compartment 22 of each header chamber.

The inner sheet 11 is further embossed as at 27 to provide passageways extending from the rear upper end of each header compartment 23 toward the rear end of the unit. These passageways communicate with a return passageway provided by an embossed flute 28 on the outer sheet 12, which extends around the side and bottom walls of the unit as best shown in Figures 1 and 2.

The bottom wall portion of the inner sheet 11 is embossed as at 29 to provide a passageway communicating with the bottom portion of the passageway formed by the flute 28, as shown in Figure 1. An outlet tube 30 is secured to the flute 29 and communicates with the passageway.

Refrigerant supplied to the compartments 22 of the header chambers by the distributing ducts 24 is not allowed to reach the level of the openings 21a in the plates 21. Therefore these openings 21a only communicate with the gas space above the liquid refrigerant in the compartments 22.

As the refrigerant boils off or gasifies in the compartments 22 the gas can enter the compartments 23 of the header chambers through the opening 21a and any unspent or liquid refriger-

ant entrained with the gases will be completely vaporized or gasified in the compartment 23 since these compartments are in heat exchange relation with the sharp freezing chamber 13 and the unspent refrigerant will absorb heat from the chamber. In the event that appreciable amounts of unspent refrigerant are splashed over into the compartment 23 the same will be heavier than the gases and will collect in the bottom of the compartments until completely gasified.

The passageways provided by the flute 27 therefore should only receive spent refrigerant which is removed from the unit through the ducts provided by the flutes 27 and 29. The outlet tube 30 therefore only receives completely spent refrigerant.

Since the spent refrigerant gases have an appreciable length of travel while still retained in the evaporator unit because they must pass through the ducts provided by the flutes 27, 28 and 29, any residual cooling capacity of the gases is absorbed by the unit.

As a result, the outlet tube 30 can never become cool enough to be frosted, and no frost back is provided in systems using evaporator units of this invention.

From the above description it will be understood that the invention now provides a heat exchanger especially adapted to be made of sheet metal and containing at least one header chamber which is divided by a baffle into a plurality of compartments which successively receive fluid circulated through the exchanger.

I claim as my invention:

35. 1. A U-shaped sheet metal evaporator unit having the constituent sheets thereof embossed to provide a header chamber in each leg of the unit, a plate between the sheets dividing the chamber into communicating compartments, embossments on the inner sheet defining ducts communicating, respectively, with one of said compartments in said header chambers, and an additional embossment providing a passageway communicating with said ducts to exhaust spent refrigerant from said compartments.
40. 2. A sheet metal U-shaped evaporator unit comprising a pair of secured-together contiguous metal sheets, said sheets being embossed to define a header chamber extending transversely across each leg of the unit, said outer sheet being further embossed to define a plurality of spaced parallel refrigerant circulating ducts connecting said header chambers, a baffle plate between the sheets in each leg of the unit dividing the header chambers into a pair of compartments, each baffle plate having an aperture therethrough joining the upper portions of the compartments separated by said baffle plate, and at least one of said sheets being further embossed to provide a spent refrigerant outlet passageway connecting the upper portions of the inner compartments of each header chamber.
45. 3. A sheet metal evaporator unit comprising a pair of secured-together contiguous metal sheets, said sheets being embossed to define a header chamber extending transversely along each leg of the unit, a baffle plate in each leg of the unit between the sheets dividing each header chamber into inner and outer compartments, said outer sheet being further embossed to define a plurality of spaced refrigerant circulating ducts connecting the outer compartments, at least one of said sheets being further embossed to define a spent refrigerant outlet passageway connecting the upper portions of the inner com-

partments, and an exhaust tube communicating with said passageway at a point remote from both inner compartments.

4. In a heat exchanger having a header chamber adapted to contain liquid refrigerant and provided with an outlet opening at one end, the improvement which comprises a partition dividing said chamber lengthwise into two compartments extending side by side, said partition being capable of preventing flow of liquid refrigerant between the compartments, said partition further having a top portion apertured at a point spaced widely from said outlet opening, whereby any fluid flowing through said aperture and thence through one of said compartments to said outlet is forced to move for a considerable distance lengthwise of said header chamber.

5. In a heat exchanger having a header chamber, the improvement which comprises a partition dividing said chamber lengthwise into two compartments extending side by side and intercommunicating solely at the top of one chamber end so as to form a U-shaped path for gasified refrigerant superimposed on two separate elongate liquid refrigerant spaces extending in the same general direction as the legs of said U.

6. A sheet metal U-shaped evaporator unit comprising a pair of secured-together contiguous embossed metal sheets and metal plates between portions of the sheets cooperating for defining inner and outer header chamber compartments in each leg of the unit, at least one of said sheets being further embossed to define a spent refrigerant outlet passageway connecting the upper portions of the inner header compartments, the bottom of the other sheet being embossed above said passageway to continue the same, and an exhaust tube communicating with the continuation of said passageway.

7. The method of preventing frost back of the refrigerant exhaust tube in a mechanical refrigerating system which comprises flowing liquid refrigerant into an elongate heat exchange zone ahead of said exhaust tube, retaining the liquid refrigerant within said heat exchange zone while evaporating the liquid refrigerant, and baffling the gasified refrigerant to flow the same along a U-shaped reversed path lengthwise of the heat exchange zone, whereby the gasified re-

frigerant can be made to absorb sufficient heat before entering the exhaust tube to eliminate frosting of the tube.

8. The method of preventing frost back of the exhaust tube in a mechanical refrigerating system which comprises flowing liquid refrigerant into one compartment of a multi-compartment header chamber ahead of said exhaust tube, retaining the liquid refrigerant in said one compartment while evaporating the liquid, and successively flowing the gasified refrigerant through said one compartment and thence through another compartment of said chamber, to enable the gasified refrigerant to absorb sufficient heat before entering the exhaust tube for eliminating frosting of the tube.

9. The method of preventing frost back of return tubes in mechanical refrigerating systems by refrigerant collected from distributing passages of an evaporator unit in a chamber superimposed upon said passages, said method comprising impeding flow of collected liquid refrigerant while permitting the same to evaporate, flowing the gasified refrigerant through a heat exchange zone spaced from the collected refrigerant, and trapping in said zone any liquid refrigerant entrained by the gasified refrigerant, whereby the gasified refrigerant will absorb sufficient heat before entering said return tubes not to frost the same.

10. In an evaporator structure shaped to provide a plurality of refrigerant ducts and an elongated header chamber in communication with said ducts to receive refrigerant therefrom, said structure having a refrigerant inlet communicating with said ducts and an exhausted refrigerant outlet communicating with the upper portion of said chamber at one end thereof, the improvement of a baffle in said header chamber dividing the chamber lengthwise thereof into two separate compartments one of which communicates with the ducts and the other of which communicates with the outlet, and said baffle having a passageway therethrough joining the upper portions of said compartments only at the end of the header chamber which is remote from the outlet end whereby liquid refrigerant is prevented from reaching said outlet.

BERNARD C. JOHNSON.
